Primary Examiner — Susan Moon Lee(74) *Attorney, Agent, or Firm* — Katten Muchin Rosenman LLP(57) **CLAIM**

The ornamental design for a pet bowl, as shown and described.

DESCRIPTION

FIG. 1 is a perspective view of a pet bowl;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The portions of the design that is shown in broken lines do not form part of the claimed design.

1 Claim, 5 Drawing Sheets# US D636,945 S
